PLASTIC CONTAINER FOR DAIRY PRODUCTS OR THE LIKE

Paul Davis, Beverly, Mass., assignor to Sweetheart Plastics, Inc., Wilmington, Mass., a corporation of Maryland

Filed June 10, 1964, Ser. No. 80,351

Term of patent 14 years

(Cl. D58—17)

FIG. 2

FIG. 3

FIG. 4

FIG. 5

FIG. 6

FIG. 1 is an elevational view of a plastic container for dairy products or the like, showing my new design;

FIG. 2 is a cross-sectional view taken along section line 2—2 of FIG. 1;

FIG. 3 is a cross-sectional view taken along section line 3—3 of FIG. 1;

FIG. 4 is a top plan view of the plastic container for dairy products or the like;

FIG. 5 is a bottom plan view of the plastic container for dairy products or the like; and

FIG. 6 is a cross-sectional view taken along the section line 6—6 of FIG. 1.

I claim:

The ornamental design for a plastic container for dairy products or the like, as shown.
